United States Patent Office

Des. 221,584
Patented Aug. 24, 1971

221,584

PORTABLE LIGHT

Julian J. Wierzbicki, Peabody, and Harold L. Hough,
Beverly, Mass., assignors to Sylvania Electric Products
Inc.

Filed July 2, 1970, Ser. No. 23,816

Term of patent 14 years

Int. Cl. D26—02

U.S. Cl. D48—24

FIG. 1

FIG. 2

FIG. 3

FIG. 4

FIG. 5

FIG. 6

FIG. 1 is a side elevational view of a portable light showing our new design;

FIG. 2 is an opposite side elevational view thereof;

FIG. 3 is a front elevational view thereof;

FIG. 4 is a rear elevational view thereof;

FIG. 5 is a top plan view thereof;

FIG. 6 is a bottom plan view thereof.

The fragmentary cord is shown in broken lines for illustrative purposes only.

We claim:

The ornamental design for a portable light, as shown and described.
